UNITED STATES PATENT OFFICE

2,164,623

HAIRPIN HOLDER

Alfred E. Posner, Dorchester, Mass.

Application January 8, 1938, Serial No. 184,050

1 Claim. (Cl. 175—367)

The present invention relates to a hair pin holder for holding a bunch of hair pins on the wrist and is principally used for a hair dresser particularly in dressing hair.

5 It is common practice in many beauty parlors, for the hair dresser, either in waving or setting the hair to give the patron a handful of hair pins, which the patron hands to the operator as they are needed. While this is unobjectionable in 10 many respects, still it is not wholly desirable to have the patron do even this little part in the hair dressing. In some shops an assists aids in doing various things and also serves to hand the operator the hair pins when needed. However it is 15 readily seen that this necessitates extra help. Attempts have been made to substitute other means for making hair pins readily available, but for the most part these have been cumbersome and actually do not save much time for even 20 merely picking up the pins from a table or tray nearby the place where the operator is working.

In the present invention the applicant has overcome these objects in that the pins are not only readily picked up by the device on the operator's wrist where it is placed but also they are 25 readily removed by the operator in such a position that they may be applied easily to the hair.

In the present invention the operator uses a 30 specific type of magnet which is shaped in a convenient fashion and which is applied to the wrist in such a way that the operator merely needs to place the wrist over the box or tray containing the hair pins which are readily picked up and in a position to be used immediately.

35 In the present invention it is assumed that the hair pins used are made of magnetic material, that is material which is responsive to magnetic flux so that they may be picked up by a magnet. Magnets for picking up articles are of course not 40 new, but the present invention resides in the specific construction of the article of manufacture which makes the device particularly useful in the present application.

Other merits and advantages of the present 45 invention will be more clearly understood from the description and drawing annexed to the present specification, in which:

Figure 1 shows a plan view of the device.

Figure 2 shows a section on the line 2—2 of 50 Figure 1, and

Figure 3 shows a detail of the shape of the magnet used in the invention.

In the figures there is used a magnet 1 of the permanent magnet type indicated in Figure 3 55 which has a substantial semi-circular outer contour and an inner contour of a horse-shoe shape forming two poles 2 and 3 across which the hair

pins may be held. In fact it will be noted that the magnet faces 2 and 3 are sufficiently far apart so that the pins will be held not only across the end pole elements 2 and 3 but also across the prongs 4 and 5. This is accomplished by having 6 the space between the pole faces 2 and 3 substantially the same width as that across the prongs 4 and 5. A band of non magnetic metal such as copper or the like extends around the end of the magnet from one side to the other side 10 as indicated in Figure 1 and Figure 2 by the numeral 6. This band is substantially U shaped in section and has as indicated in Figure 1 a face of a disc or plate shape as indicated by 7 in Figure 1 which covers the entire opening in the center 15 of the magnet and extends substantially over the sides of the magnet holding in place on one side the wrist strap 8 of leather or other material, which is likewise larger in area where it is held to the magnet as shown at 9 in Figure 1. A screw 20 10 or other similar means is used to clamp the two plate members 7 of the band together and hold the leather strap tightly in place against the magnet. In this way the magnet is entirely covered and offers no place for the pins to catch and 25 prevent their easy removal.

In the operation of the device, the operator has the article applied to his wrist like a wrist watch. He dips his wrist into the pin tray and the pins 30 lay on flat on the magnet across from pole to pole or prong to prong in generally the same direction. The operator removes them by merely plucking them off of the holder, the top ones being plucked off first until they all are used up.

If the pins in the tray are all faced in the same 35 direction, they will be picked up in the same manner by the magnet and the operator therefore does not need to look at the holder or the pins as he takes them in his hands. A sufficient number of pins may be picked up at once so that the operator is not compelled to reach to the tray but very few times even during a type of hair dressing in which a great many pins are used.

Having now described my invention, I claim:

Means for holding hair pins comprising a horse 45 shoe magnet, a non magnetic member having two opposed plates positioned over the inner periphery of the horse shoe substantially covering the same with a portion extending around the open end of the horse shoe substantially in line 50 with the pole faces of the horse shoe magnet and joined to the said plates, a strap inserted between the face of the horse shoe magnet and one of said plates and means clamping said opposed plates against the faces of the horse shoe magnet. 55

ALFRED E. POSNER.
